[57] **CLAIM**

The ornamental design for a packaging container, as shown and described.

DESCRIPTION

FIG. 1 is a top perspective view of a packaging container showing our new design, the dash lines representing score lines;

FIG. 2 is a view similar to FIG. 1 but showing the packaging container in an open condition;

FIG. 3 is a side elevational view showing the side opposite that seen in FIG. 1;

FIG. 4 is an end elevational view; and

FIG. 5 is a bottom plan view.

The characteristic feature of our design resides in the appearance and configuration of the opening area on the container shown.
